UNITED STATES PATENT OFFICE.

BENJAMIN A. SLOCUM, OF LYNN, MASSACHUSETTS, ASSIGNOR TO BOSTON MACHINE WORKS COMPANY, OF LYNN, MASSACHUSETTS, A CORPORATION OF MASSACHUSETTS.

VAMP-FOLDING MACHINE.

No. 918,383.

Specification of Letters Patent.

Patented April 13, 1909.

Application filed November 15, 1904. Serial No. 232,781.

To all whom it may concern:

Be it known that I, BENJAMIN A. SLOCUM, of Lynn, county of Essex, and Commonwealth of Massachusetts, have invented certain Improvements in Vamp-Folding Machines, of which the following, read in connection with the accompanying drawings, is a specification.

This invention relates to machines intended for folding the reentrant curved inner edges of vamps of boots and shoes.

The novelty of the invention consists in construction and working operations of the folder members whereby it is specially adapted for folding the reentrant or curved edge of shoe vamps, and in the actuating mechanism for the folder members and in the combination of a plurality of folding elements arranged in sets of varying size with a single actuating mechanism and supporting frames therefor which are movable relatively for placing the actuating mechanism and sets of folding elements in coöperative work position at different times.

It also relates to matters of construction all of which are more specifically described hereinafter.

Of the drawings, Figure 1 is a front elevation showing the machine partly in section. Fig. 2 shows a detail detached. Fig. 3 shows the machine with folder elements and yoke S removed. Fig. 4 shows the table plate and folder members detached. Fig. 5 shows the former plates detached. Fig. 6 is a plan view with a portion of the yoke removed showing the folding plates, and Fig. 7 is a sectional detail.

The machine comprises a frame B suitably arranged with uprights 6 to support the shaft 2. On the shaft 2 are cams 3, 4, 5, 6, 7, 8 and concentric with the shaft 2 is a part 10 which is held against rotation, it being for that purpose clamped between the cap-plates 12 and arms 14, 14 by screws (not shown). This part 10 serves for an axle on which to support the hubs 20, 22 which carry duplicate arm-radii of which two only 24, 26 will be described. The arms 24, 26 support a frame A which carries the yoke S and the operative parts operated through rods 28, 30, 32, 34

which to that end are suitably arranged in the part 10 for movement by the cams 4, 5, 6, 7, respectively.

The yoke S is supported on rods 45, 48 which slide in the frame A, thereby permitting movement toward and from the frame A. On the rods 45, 48 are studs 50, 52 in line to be engaged by the slides 54, 56, which being arranged to slide in the standards 16, 18 carry rollers 40, 42 engaged respectively with the cams 3-8 whereby the necessary lowering movements of the yoke S are effected. Such movements are effected against the tension of springs 44, 46 which operate for lifting the yoke S whenever the cams 3, 8 permit.

From the foregoing description it will be understood how the different sets of mechanisms comprising the yoke S, frame A and the folding elements mounted thereupon may be supported on the arm radii of the hubs 20, 22 and each set being brought to the working position by the operator when required for use. The connecting parts which bear on rods 28, 30, 32, 34 are provided with anti-friction rollers, as shown, to facilitate this movement. The different sets of folding elements vary in size only, so that a description of one set only is presented.

The folding elements include plates 60, 62, 64 66, 68. The table plate 60 has an inwardly curved edge contour 70 which corresponds with the reentrant curve or line of fold to be given the material operated upon. It is fixed upon the frame A and supports the vamp to be folded. The former comprises plate 62 having the curved edge contour 72 which corresponds to a section approximately one half of the edge contour 70 of plate 60, and the coöperating plate 64 having the curved edge contour 74 which corresponds with a section approximately the other half of the edge contour 70.

In operation of the machine, the material being placed upon plate 60 with its edge projecting over the line 70 and against the ribs X, X the former plates 62, 64 are then pressed down upon the material. To this end, the plates 62, 64 are supported respectively on pins 80, 82, 84, 86 and carried by 100

the yoke S, the plates being relatively adjusted so that as the yoke S is lowered by cams 3, 8, the plates 62, 64 will position upon the material with their edge faces 72, 74 in the same vertical plane with the edge face 70 of said plate 60. The edge part of the material will now occupy a position over the edge of the underlying folder plates 66, 68, and will be upturned against the edges 72, 10 74 by uplifting the plates 66, 68 which is done in the next operation of the machine.

The folder member 66 has a curved edge contour 76 which is contour to approximately one half of the edge contour 70 and 15 the folder member 68 has a curved edge contour 78 which is contour to approximately the other half of the edge contour 70. The folder member 66 is fixed upon the rod 90 which is mounted in the block 92, such 20 block is arranged to slide in the frame A for purposes stated hereinafter. On the rod 90 is a coiled spring 94 which is contracted between the block 92 and shoulder on the rod 90 and operates to hold the rod 90 with 25 its bottom end pressed on the rod 30. In like manner the folder member 68 is supported on the rod 96 which is mounted in the slide 98 and depressed on the rod 32 by a spring 200. Said rod 96 slide 98 and 30 spring 200 being constructed and arranged like the rod 90 slide 92 and spring 94 and are not therefore shown in detail.

It will now be understood how the folder members 66, 68 are lifted by the cams 5, 6 35 respectively operating through rods 30, 90, and 32, 96. The members 66, 68, having been uplifted, the next operation is to advance these members for folding and wiping the material over the former plates 62, 64, 40 and herein resides an important feature of this invention. In this connection the members 66, 68 are caused to advance in divergent paths running acutely angular to the median line of the former. The ad- 45 vance movement of slide 92 and consequently the folder member 66 is effected by the cam 4 operating through the rod 28 and the toggle 206, such toggle being pivoted at one end to the slide 92 and by its other end 50 to the frame A. The advance of the slide 92 is made against the coiled spring 208 whereby the slide is moved to the rearward position again whenever the cam 4 permits. In like manner the slide 98 and consequently 55 the folder 68 is advanced by the cam 7 operating through the rod 34 and toggle 210, such advance is against the coiled spring 2² whereby the slide is returned to the rear position whenever the cam 7 permits.

60 After the members 66, 68 have been advanced for wiping the material over the former it becomes necessary for drawing the former plates 62, 64 from under the over-

wiped material. To this end a mechanism is employed in connection with each of the 65 former plates, such mechanisms being duplicates, and one set only is described herein. The pins 80, 82 carrying the former plate 62 are mounted in a slide 226 (Fig. 2) which slide is arranged for movement endwise in 70 the yoke S. Pivoted on the yoke S is a rock lever 228 of the bell-crank type. One arm of this lever engages the slide 226 and the other arm bears upon the pin 230 which is arranged in the yoke S for movement endwise against one end of the lever 228 causing the other end of the lever to engage the slide 226 and moving it against the spring 221. It will now be understood how, as the yoke S moves down, the pin 230 becomes engaged 80 with the work and uplifting raises one arm of the lever 228, thereby causing the other arm to move the slide 226 which carries the pins 80, 82 and consequently the plate 62 forward, thereby removing the plate 62 from 85 under the overturned material. A duplicate mechanism operated by the pin 300 will simultaneously remove the plate 64, whereupon the yoke S descending farther bears upon the ribs X, X, thereby clamping and 90 setting the folded material between the folder plates 66, 68 and bed-plate 60. The cams 3, 8 thereupon release the yoke S which is lifted by springs 44, 46, the folding elements being simultaneously returned to 95 their positions for beginning another operation.

It will be understood that in the advance movement of the folder members 66, 68 in divergent paths for wiping over the material 100 these plates become spaced apart, and I have provided the auxiliary plate 306, which is mounted on the yoke S in position for operating between the folder members to press the material at this point.

Having now described my invention I claim—

1. The combination with two frames, a shaft journaled in bearings on one of said frames, a yoke carried by the other frame, 110 cams secured on the shaft, standards, slides connected with the standards and controlled by cams on the shaft for moving the yoke in one direction, of a table, folder plates having sliding connection in two different directions 115 with the yoke, folder members carried by one of the frames and moved in two different directions at right angles to each other by cams on the shaft.

2. The combination with a frame and shaft revolvably supported therein and carrying cams, of a folder comprising the fixed table 60, folder plates 62 and 64 located above said table, means for raising and lowering said folder plates, and means for moving them edge-wise, folder members 66 and 125

68 raised and lowered by one set of cams on the shaft, and moved edge-wise by another set.

3. The combination with a frame, a yoke and means for moving the yoke positively with respect to the frame, of a fixed table, folder members, folder plates, the latter yieldingly connected with the yoke, means for sliding said folder plates edge-wise when 10 they have reached the predetermined posi-

tion, a shaft, rods for moving said parts in one direction and toggles for sliding them in another direction.

Signed by me at Lynn, Massachusetts, this 12 day of Nov. 1904.

BENJAMIN A. SLOCUM.
